VALVE MECHANISM FOR ROCK DRILLS

Application filed December 14, 1928. Serial No. 325,987.

This invention relates to rock drills, but more particularly to a valve mechanism for distributing the pressure fluid to rock drills of the hammer type.

5 The objects of the invention are to obtain a heavy blow of the hammer piston against the working implement and to use the pressure fluid expansively so that the pressure fluid consumption for actuating the drill will be held to a minimum.

10 Other objects will be in part obvious and in part pointed out hereinafter.

In the drawings illustrating the invention and in which similar reference characters refer to similar parts,

15 Figure 1 is a diagrammatic view in sectional elevation of a rock drill equipped with valve mechanism constructed in accordance with the practice of the invention and illustrating the valves and the piston in one of their limiting positions, and

20 Figure 2 is a view similar to Figure 1 showing the valves and the piston in another extreme position.

25 Referring more particularly to the drawings, A represents a cylinder of a rock drill having a piston chamber B in which is disposed a reciprocating piston C. The piston C has a reduced extension D for delivering blows to a working implement, such as a drill steel E supported and guided by the front end of the drill. In the construction shown the cylinder A has a free exhaust port F which is controlled by the piston C.

30 For simplicity of illustration, the cylinder A is shown as having an integral valve chest G in which is formed a valve chamber H having enlarged pressure chambers J and K at its forward and rearward ends respectively.

35 The bore comprising the valve chamber H may extend entirely through the valve chest G and in the ends thereof are disposed closures in the form of hollow plugs L which are held securely in position by a bolt O pro-

vided with a nut or nuts P whereby the plugs L are clamped in position.

40 Pressure fluid for actuating the drill may be conveyed from a suitable source of supply (not shown) through a connection Q which is threaded into the valve chest G for introducing pressure fluid into the intermediate or restricted portion R of the valve chamber H. From opposite ends of the restricted portion R of the valve chamber lead inlet passages S and T to the piston chamber B. The inlet passage S leads from the forward end of the restricted portion R of the valve chamber to the corresponding end of the piston chamber, and the inlet passage T leads from the rearward end of the restricted portion R to the rearward end of the piston chamber.

45 The admission of pressure fluid to the front end of the piston chamber B is controlled by a distributing valve U which is of the differential type and has a head V which lies in the pressure chamber J and an integral extension W which extends into the forward end of the restricted portion R. A similar valve X is disposed in the pressure chamber K and has a head Y in the pressure chamber K and an extension Z which extends into the rearward end of the restricted portion R and controls the inlet passage T. Due to this arrangement of the valves U and X the operating or innermost pressure surfaces b are constantly exposed to pressure fluid in the valve chamber H tending to open the valves.

50 The outermost ends of the valves U and X constitute pressure surfaces c against which pressure fluid may act intermittently for closing the valves. The admission of such pressure fluid into the pressure chambers J and K is in this instance controlled by the piston C which overruns tripper ports d and e.

55 The tripper port d leads from a point in the piston chamber B rearwardly of the free exhaust port F to the front end of the pressure chamber J and the tripper passage e

60 65 70 75 80 85 90

leads from a point forwardly of the free exhaust port F to the rearward end of the pressure chamber K. The tripper passages d and e are in constant communication with the valve chamber H through leak passages f and g in the valve chest G so that pressure fluid will be constantly flowing into the tripper passages.

In order to partially relieve the compression in the ends of the piston chamber B, a compression relief passage h is formed in the valve chest G to lead from the inlet passage S to the pressure chamber K. The relief passage h opens into the pressure chamber K at a point intermediate the ends thereof so that it may be covered by the head Y of the valve X in one of the positions of the valve. Similarly a compression relief passage j leads from the inlet passage T to the pressure chamber J for relieving the compression in the rearward end of the piston chamber. The relief passage j also opens into the pressure chamber J at a point intermediate the ends so that in the closed position of the valve U, the head Y of said valve will close the said passage j. In the innermost ends of the pressure chambers J and K are vents k and o respectively for conveying the compression flowing from the pressure chamber to the atmosphere.

The operation of the device is as follows: With the valves U and X and the piston C in the positions illustrated in Figure 1, pressure fluid will flow from the valve chamber H through the inlet passage T into the rearward end of the piston chamber B to impel the piston C forwardly. While the piston C is in the rearward end of the piston chamber, it covers the tripper passage d so that pressure fluid flowing through the leak passage f into said tripper passage and into the chamber J will act against the pressure surface c of the valve U to hold said valve closed.

Pressure fluid will of course also be flowing through the leak passage g and the tripper passage e, but since the tripper passage e is in direct communication with the main exhaust port F, the pressure fluid in the tripper passage e will be ineffective to move the valve X against the full line pressure acting against the pressure surface b for holding the valve X open.

As the piston C proceeds in a forwardly direction, the compression in the front end of the piston chamber will flow through the inlet passage S and the compression relief passage h into the pressure chamber K from whence it will escape to the atmosphere through the vent o.

At about the time the piston C uncovers the tripper passage d, it will cover the tripper passage e and pressure fluid will then immediately flow into the pressure chamber K to act against the pressure surfaces c of the valve X for closing said valve. Imme-

diately thereafter the main exhaust port F will be uncovered by the piston and the pressure fluid utilized for actuating the piston C forwardly, together with the pressure fluid acting against the pressure surface c of the valve U will thence escape to the atmosphere.

In these positions of the piston C and the valve U, the live pressure fluid in the valve chamber H, acting on the pressure surface b of the valve U will open said valve and pressure fluid will then flow through the inlet passage S into the front end of the piston chamber B to retract the piston. Meanwhile the valve X will be held closed by the pressure fluid flowing through the leak passage g and the tripper passage e into the outer end of the pressure chamber K.

During the rearward movement of the piston C, the tripper passage d will be covered by the piston so that the pressure fluid flowing into the said tripper passage from the leak passage f will act against the pressure surface c of the valve U for closing said valve. Continued rearward movement of the piston C will place the tripper passage e into communication with the exhaust port F so that the pressure fluid used for holding the valve X closed may then escape to the atmosphere. When this occurs the pressure fluid acting against the pressure surface d of the valve X will again open the valve.

After the piston C has covered the exhaust port F during the rearward travel of the piston, the compression in the rearward end of the piston chamber B will flow through the inlet passage T thence through the compression relief passage j into the pressure chamber J from whence it will escape to the atmosphere through the vent k. From this point on the cycle of operations may be repeated.

The present invention has been found particularly efficient for use in distributing the pressure fluid to rock drills of the hammer type. Due to the arrangement of the various passages and ports, the pressure fluid which actuates the piston C may be used expansively, that is, the admission of pressure fluid into the ends of the piston chamber may be cut off at any suitable point in the travel of the piston before the exhaust port F is uncovered. As a result a heavy blow of the piston C will be obtained and a great saving in the matter of pressure fluid consumption may be effected.

We claim:

1. In a fluid actuated rock drill, the combination of a cylinder and a piston, an exhaust port for the cylinder controlled by the piston, a valve chamber, inlet passages leading from the valve chamber to the cylinder, valves in the ends of the valve chamber for controlling the inlet passages, said valves being constantly exposed at one end to pressure fluid for actuating them in one direction,

tripper passages leading from the cylinder to the ends of the valve chamber and opening into the cylinder at points between the exhaust port and the ends of the cylinder to enable said tripper passages to be covered by the piston before the piston uncovers the exhaust port, and leak passages constantly conveying pressure fluid into the tripper passages for throwing the valves in the other direction when the piston covers the tripper passages.

2. In a fluid actuated rock drill, the combination of a cylinder and a piston, an exhaust port for the cylinder controlled by the piston, a valve chamber, inlet passages leading from the valve chamber to the cylinder, valves in the ends of the valve chamber for controlling the inlet passages, said valves being constantly exposed at one end to pressure fluid for actuating them in one direction, crossed tripper passages leading from the ends of the valve chamber and opening into the cylinder at points intermediate the exhaust port and the ends of the cylinder, said tripper passages being covered by the piston before the piston uncovers the exhaust port, and leak passages constantly conveying pressure fluid into the tripper passages for throwing the valves in the other direction when the piston covers the tripper passages.

3. In a fluid actuated rock drill, the combination of a cylinder and a piston, a main exhaust port for the cylinder controlled by the piston, a valve chamber having enlarged pressure chambers at its ends, inlet passages leading from the valve chamber to the cylinder, compression relief passages leading from the inlet passages to the pressure chambers, vents leading from the pressure chambers for conveying compression from the said pressure chambers to the atmosphere, differential valves in the pressure chambers controlling the inlet passages and compression relief passages, said valves being constantly exposed to pressure fluid at their small ends for opening the valves, crossed tripper passages leading from the pressure chambers to the cylinder, and leak passages constantly conveying pressure fluid from the valve chamber into the tripper passages for closing the valves when the piston covers the tripper passages.

4. In a fluid actuated rock drill, the combination of a cylinder and a piston therein, a main exhaust port for the cylinder controlled by the piston, a valve chamber having an intermediate restricted portion and enlarged pressure chambers at its ends, inlet passages leading from the restricted portion of the valve chamber to the ends of the cylinder, compression relief passages affording communication between the inlet passages and the pressure chambers, vents leading from the inner ends of the pressure chambers for conveying compression from the said pressure chambers to the atmosphere, dif-

ferential valves in the pressure chambers to control the inlet passages and having heads to control the relief passages, said valves being constantly exposed to pressure fluid at their small ends for opening the valves, crossed tripper passages leading from the pressure chambers to the cylinder, and leak passages constantly conveying pressure fluid from the valve chamber into the tripper passages for closing the valves when the piston covers the tripper passages.

In testimony whereof we have signed this specification.
